(57) **CLAIM**

The ornamental design for a surgical manual driver, as shown
and described.

DESCRIPTION

FIG. 1 is a perspective view of a surgical manual driver,
showing my new design;

FIG. 2 is a top elevational view thereof;

FIG. 3 is a bottom elevational view thereof;

FIG. 4 is a right side elevational view thereof, the opposite
side being a mirror image;

FIG. 5 is a front elevational view thereof;

FIG. 6 is a rear elevational view thereof;

FIG. 7 is a top elevational view of the surgical manual driver
of FIG. 1 with the sleeve removed;

FIG. 8 is a bottom elevational view of the surgical manual
driver of FIG. 1 with the sleeve removed;

FIG. 9 is a left side elevational view of the surgical manual
driver of FIG. 1 with the sleeve removed;

FIG. 10 is a right side elevational view of the surgical manual
driver of FIG. 1 with the sleeve removed;

FIG. 11 is a front elevational view of the surgical manual
driver of FIG. 1 with the sleeve removed;

FIG. 12 is a rear elevational view of the surgical manual driver
of FIG. 1 with the sleeve removed; and,

FIG. 13 is a perspective view of the surgical manual driver of
FIG. 1, showing a dental drill in phantom.

The broken line showing is for environmental purposes only
and forms no part of the claimed design.
